UNITED STATES PATENT OFFICE

172,859

TELLER'S DEPOSITORY BOOTH

Leland W. Belew, Hamilton, Ohio, assignor to Herring-Hall-Marvin Safe Company, Hamilton, Ohio, a corporation of Ohio

Application October 2, 1953, Serial No. 27,061

Term of patent 14 years

(Cl. D13—1)

To all whom it may concern:

Be it known that I, Leland W. Belew, a citizen of the United States and resident of Hamilton, Ohio, whose post office address is 516 Harrison Avenue, Hamilton, Ohio, have invented a new, original, and ornamental Design for Teller's Depository Booth, of which the following is a specification, reference being had to the accompanying drawings showing my new design, forming part thereof.

The design is characterized by a counter portion which is centrally divided by a transverse channel which extends entirely across the counter from front to rear and houses the front drawer and the inset closure therefor, the outer face of the drawer being presented symmetrically in the front wall of the bay.

I claim:

The ornamental design for a teller's depository booth, as shown and described.
